UNITED STATES PATENT OFFICE

FREDERICK HURSH WRIGHT, OF LONDON, AND EDMUND WOODWARD LEWIS, OF LEISTON, ENGLAND, ASSIGNORS TO THE CENTURY MACHINE COMPANY, OF CINCINNATI, OHIO

SAFETY LOCKING DEVICE

Application filed November 8, 1929, Serial No. 405,819, and in Great Britain January 16, 1929.

This invention relates to machines for mincing meat, and is an improvement in or modification of the safety devices described in United States Patent #1,782,084, dated November 18, 1930.

The objects of the present invention are firstly, to improve the safety catch locking the cover to the knife bowl in such a manner that the working parts are enclosed as much as possible; secondly, to simplify the safety locking of the handles controlling the clutch on the knife spindle and the motor switch; thirdly, to employ a mechanical governor control instead of an electro-magnetic control 15 to retain the cover closed until the moving parts have lost their momentum and are at rest; and fourthly, a simplification of the clutch driving the bowl.

According to this invention, the opening 20 and closing movement of the cover of the knife bowl causes the lug or pin thereof to engage in an open slot of a cam piece secured on the outer end of a short shaft which projects through a casing enclosing the sliding bolt or catch. On the inner end of this shaft is fixed a boss with oppositely disposed stops 25 or projections, one of which is either in the path of a lug on the end of the sliding bolt, or is turned down to permit the bolt to slide, and the bolt in its new position holds the stop 30 down; the other stop is engaged by a flat blade spring.

The trip levers of the prior specification are replaced by a single lever pivoted at or 35 near its centre about midway between the two hand levers controlling the clutch mechanism and motor switch respectively, and the spindle of each hand lever is provided with a grooved or notched disc which co-acts with 40 the corresponding end of the pivoted lever. By this device, the switch must first be turned off before the clutch can be disconnected and the cover opened, and the switch is then automatically locked so long as the cover remains 45 open.

The governor control which replaces the electro-magnetic rheostat is mounted on the vertical shaft which is directly geared to the motor shaft, and a sliding collar on the governor shaft is pushed by the governor against

a hanging catchpiece and holds it in the path of a projection fixed on the clutch link mechanism, thereby locking such mechanism until the speed of the governor falls sufficiently to lower the collar and release the hanging catchpiece. 55

The shaft driving the bowl is operated through a clutch independently controlled by a separate handle, and is not directly subject to the controls described above. 60

The invention is illustrated in the accompanying drawings in which:—

Figure 1 is an elevation of the machine partly in section and with part of the lower cover removed to show the safety locking 65 control, the switch being off and the clutches in neutral position.

Figure 2 is an end elevation of the machine with the end cover removed.

Figure 3 shows the safety locking control 70 when the mincer only is working.

Figure 4 shows the cam and boss which are operated by the hinged cover of the knife bowl, the parts being in the position in which the sliding bolt is locked and the cover is 75 open.

Figure 5 shows the same parts as in Figure 4 but turned through a right angle by the descent of the cover, leaving the sliding bolt clear of its stop. 80

Figure 6 is a plan view of the device shown in Figure 1.

The machine, as in the prior specification comprises a main framing A which carries a mincer B, cutter C, and motor D. The clutch E on the motor shaft drives the spindle F of the cutter knives G, and the mincer B is driven from the motor D by worm gearing H, I, vertical shaft J, clutch K, and worm gearing M. 85

The first improvement under the present invention relates as described above to the locking of the cover *a* of the knife bowl, which cover is swingingly supported on a pipe *p*. For this purpose there is provided a short shaft 1 which projects through the casing 2 enclosing the sliding bolt or catch *d*, and to the outer end of the shaft 1 is fixed a cam piece 3 having an open slot 4 as shown in Figures 4 and 5, this slot being in the path 95 of the projection 5 of the clutch link mechanism. 100

of a lug or pin a' on the cover a . The lug or pin a' conveniently is in the form of a bar which is fixed to an upstanding flange a^2 by means of bolts a^3 so as to lie in the path of the cam piece 3. On the inner end of the shaft 1 is fixed a boss 5 provided with stops or projections 6, 7. The stop 6, in the position shown in Figure 4 is interposed in the path of the rearwardly-turned end d^2 of the sliding bolt d , 10 the cover a being partly or wholly raised; the bolt d with its operating linkage o^1, k is thus locked, and the stop d^1 fixed to the bolt, holds the clutch E out of engagement. At the same time the boss 5 is held firmly by the spring 15 8 engaging the projection 7. When the cover is closed, the projection a' turns the cam 3, and the boss 5 assumes the position shown in Figure 5, carrying the stop 6 downwards out of the path of the rearwardly-turned end 20 d^2 of the bolt, and the projection 7 is again held firmly in its new position by the spring 8. The bolt may now be shifted by the handle g to bring the clutch E into engagement, and the end d^2 of the bolt now prevents the 25 stop 6 from turning back.

The hand lever g can be turned to start either the mincer or the cutter; in the position of the lever g shown in full lines in Figure 3, the mincer clutch K is brought into 30 operation, and in the diametrically opposite position of the lever g the cutter clutch E is brought into operation.

By this device the cover cannot be opened until the clutch E has been disconnected, and 35 the clutch cannot be again connected until the cover has been closed.

The second improvement of the present invention relates to the safety locking of the hand levers g, v , the latter being the motor 40 switch handle. Referring to Figure 3, both ends of the trip lever u are formed as projections u^4, u^5 , which tend to enter grooves or notches in the edges of circular disc v^2, g^2 , secured to the spindles of the handles v, g . 45 The disc g^2 has two opposite grooves or notches g^3, g^4 , one or the other of which is engaged by the projection u^5 when the corresponding clutch is in gear. The disc v^2 has a single groove or notch v^3 and a projection v^4 . When the switch is on as shown 50 in Figure 3, the projection v^4 engages in a groove u^3 on the trip lever u and tilts the lever so that the end u^5 engages in the notch g^4 ; the handle g cannot then be turned until the 55 switch handle v is turned over to its off position shown in dotted lines, thus bringing the groove v^3 over to allow the end u^4 to enter and free the lever u . The handle g may now be turned to the neutral position shown in the 60 dotted lines in Figures 1 and 3, thus bringing the circular edge of the disc g^2 to bear on the end u^5 as shown in Figure 1 and locking the switch handle v in its off position.

The disc g^2 carries a roller i which engages 65 in an open slot k^1 of the link k ; the link k

and sliding bolt d are therefore locked whenever the handle g is locked, even if the bolt d is free from the stop 6.

The third improvement, namely the mechanical governor control to lock the clutch-operating linkage after the switch has been turned off and until the revolving parts have lost their momentum, is shown in Figure 2 and consists of a centrifugal governor 9 mounted on the shaft J, a collar 10 sliding 70 on the shaft and pushed by the governor against a hanging catchpiece 11 when the machine is running and a projection 12 secured to the yoke l which operates the mincer clutch K and is connected by a bell-crank lever l^1 to the link k . The catchpiece 11 is thus tilted into the path of the projection 12, either above or below it according to whether the mincer or cutter is working thus locking the linkage k, l . When the switch has been turned off and the speed of the shaft 75 J is reduced, the collar 10 is lowered to free the catchpiece 11 from the projection 12. The handle g may then be actuated to disconnect the clutch; if this is the cutter clutch E, the 80 cover a can then be opened.

The fourth improvement relates to the driving of the knife bowl C. In the prior specification, a clutch was provided at the lower end of the shaft J to drive the shaft O, and worm wheel P secured to the spindle of the bowl. By the present improvement the shaft O is driven provided with a clutch 13 which is operated by a separate handle 14 and is driven from the worm N on the shaft 95 J. The clutch 13 is independent of the controls described above.

What we claim is:—

1. A safety locking device for meat mincing machines of the type including knives, an operating shaft for the knives including a clutch and a cover for the knives, said safety locking device including a sliding bolt controlling the clutch, a stop cooperating with the bolt and movable to either of two positions, said stop in the first position serving to maintain the bolt fixed against operative movement in a position to hold the clutch disengaged, said stop in a second position permitting movement of the bolt in a direction and to an extent to permit the clutch to engage, and cooperating means carried by the cover and stop to operate the stop in the movement of the cover, said cooperating means in the opening movement of the cover serving to move the stop to the first position, said cooperating means in the closing movement of the cover serving to move the stop to the second position.

2. A safety locking device as defined in claim 1, including a spring cooperating with the stop to hold it against casual movement in either the first or second position.

3. A safety locking device as in claim 1, including a governor operating a sliding col-

lar serving to hold a hanging catch piece in the path of a projection on the clutch link mechanism.

In witness whereof we have hereunto
5 signed our names.

FREDERICK HURSH WRIGHT.
EDMUND WOODWARD LEWIS.
